(57) **CLAIM**

The ornamental design for a six segment spindle assembly
for use in a tire bead winding assembly, as shown and
described.

DESCRIPTION

FIG. 1 is a front perspective view of a six segment spindle
assembly for use in a tire bead winding assembly;

FIG. 2 is a rear perspective view thereof;

FIG. 3 is a top plan view thereof;

FIG. 4 is a front elevational view thereof;

FIG. 5 is a rear elevational view thereof; and,

FIG. 6 is a bottom plan view thereof.
